(57) **CLAIM**

The ornamental design of a drill press, as shown and described.

DESCRIPTION

FIG. 1 is a perspective view taken from the front, top, right side of the drill press showing our new design;

FIG. 2 is a perspective view taken from the top, front, left side thereof;

FIG. 3 is a perspective view taken from the bottom, back, right side thereof;

FIG. 4 is a perspective view taken from the bottom, back, left side thereof;

FIG. 5 is a front elevational view thereof;

FIG. 6 is a back elevational view thereof;

FIG. 7 is a right side elevational view thereof;

FIG. 8 is a left side elevational view thereof;

FIG. 9 is a top plan view thereof; and,

FIG. 10 is a bottom plan view thereof.

Portions shown in broken lines are for illustrative purposes only and form no part of the claimed design.
